UNITED STATES PATENT OFFICE.

CHARLES O. HOLLIDAY, OF KEARNEY, NEBRASKA, ASSIGNOR OF ONE-HALF TO JOSEPH A. RICHTER, OF KEARNEY, NEBRASKA.

WASHING-MACHINE.

1,102,268.

Specification of Letters Patent.

Patented July 7, 1914.

Application filed April 5, 1912. Serial No. 688,730.

To all whom it may concern:

Be it known that I, CHARLES O. HOLLIDAY, citizen of the United States, residing at Kearney, in the county of Buffalo and 5 State of Nebraska, have invented certain new and useful Improvements in Washing-Machines, of which the following is a specification.

This invention relates to improvements in 10 washing machines, and has for one of its objects to improve the construction and increase the efficiency and utility of devices of this character.

Another object of the invention is to provide 15 a simply constructed device of this character wherein provision is made for separating the parts for the purpose of cleansing or repairs.

Another object of the invention is to provide 20 a device of this character which may be constructed of any required size and operative by hand or other power as may be preferred.

With these and other objects in view, the 25 invention consists in certain novel features of construction as hereinafter shown and described, and then specifically pointed out in the claims, and in the drawings illustrative of the preferred embodiment of the invention: Figure 1 is a side elevation of the improved machine; Fig. 2 is a front elevation of the same; Fig. 3 is a section on the line 3—3 of Fig. 1; Fig. 4 is a section on the line 4—4 of Fig. 2.

Corresponding and like parts are referred 35 to in the following description and indicated in all the views of the accompanying drawing by the same reference characters.

The improved device comprises a supporting frame including spaced side rails 10—11 and transverse members 12—13, the side members being suitably supported by legs 14 and with hand-grips formed at the terminals of the side members. Supported 40 between the side members 10—11 and likewise between the transverse members 12—13, is the receptacle or "tub" portion of the improved device which is preferably formed cylindrical in outline and comprises end members 15—16, preferably of wood, and a shell or body 17 preferably of sheet metal such as galvanized iron or the like. At its 45 upper edges the body 17 is bent over the adjacent portions of the members 12—13 in the form of flanges 18—19, as shown, so

that the shell is supported firmly in position. The upper edge of the tub portion of the device is thus located substantially level with the upper faces of the side members 10—11 and the transverse members 12—13 as shown. The side rails 10—11 are recessed intermediate their ends, as shown at 50 60 20 to receive blocks 21—22 having half bearings in their confronting faces to receive stub shafts 23—24. The blocks 21—22 are united, by clamp bolts represented at 25, which extend through the side rails 10—11 and thus not only unite the blocks to the side rails, but likewise unite the cap portions of the bearings in position upon the 70 shaft.

Bearing upon the tub or receptacle portion of the device, is a cover formed with end members 26—27 and segmental sheet metal portions 28—29, and upwardly directed end members 30—31, the sides 26—27 being continued upwardly as shown to receive the ends of the members 30—31. The segmental plates 28—29 are extended beneath the members 30—31 and thence extended upwardly against the inner face of the same to form a water-tight joint. By this means the cover portion is extended upwardly and is provided with a detachable closure 32. Mounted upon the inner ends 75 80 of the stub shafts 23—24 is a drum formed with circular end members 33—34, and a segmental sheet metal shell 35. At one side the shell 35 is provided with a relatively large opening covered by a closure 37 which is hinged at 38 to the body of the shell at one side of the opening, and bears at 39 over the opposite side of the opening. The member 37 is curved to correspond to the body 90 95 of the shell, so that when closed the shell presents a uniform cylindrical drum-like appearance. Any suitable means may be employed for holding the closure 37 in position, such for instance as a staple and pin represented at 40.

One of the stub shafts, for instance the stub shaft 24, is provided with a relatively large gear 41 engaging with a relatively small gear 42 mounted upon a stud 43, and provided with an operating handle 44. By 100 105 this simple means it will be obvious that the drum may be rotated at reduced speed by power applied to the crank 44.

The shell 35 is provided at suitable intervals with longitudinal openings having 110

guideways 36 along their edges to slidably receive frames covered by screen material represented at 45, while the cover 37 is also provided with one of the apertures having 5 a pair of the guideways and a slidable frame covered by a screen 46, the openings and their screens being preferably located at uniform distances apart. Depending from the inner face of the shell 35, and likewise of 10 the cover 37, are V-shaped deflector members 47 each of the deflectors being located adjacent to one of the screen-covered apertures, as shown in Fig. 3. Secured to the outer face of the shell 35 and of the cover 37, are 15 a plurality of hoods 48, each of the screen-covered apertures being provided with one of the covering hoods, as shown. The hoods are triangular in shape and open at one side, and as the shell is rotated the hoods pick 20 up the water as they pass through the tub and carry it upwardly and discharge it into the interior of the drum, and against the deflectors 47 which thus operate to throw the water toward the center of the drum and 25 upon the garments, as hereafter explained.

One of the deflectors 47 is located at the inner edge of each of the screen-covered apertures as shown, and thus causes the cleansing liquid to be consecutively dashed 30 against the garments as the drum is rotated.

The inner converging terminals of the hoods 48 merge substantially into the adjacent portions of the deflector 47, so that the water caught up by the hoods is caused 35 to flow without material retardation against the deflectors and its force thereby materially increased and thrown with accelerated force against the garments in the drums.

The screen covered opening being located 40 in close proximity to the deflectors and the deflectors projecting for a considerable distance into the drum, the garments are thereby held away from the screens and are thus prevented from clogging them and at the 45 same time prevented from interfering with the free flow of the water from the hoods against the deflectors. This is an important advantage in applicant's device and materially increases its efficiency and utility.

50 The end members 26-27 of the cover are provided respectively with small hoods or covers 49-50 which extend over the upwardly projecting portions of the block members 21, and thus protect the blocks and 55 their bearings.

With an apparatus constructed as described, the operation is as follows: The cover is removed and the closure 37 opened and the garments inserted into the revolving 60 drum and the cover closed. The garments may be inserted into the drum before the lat-

ter is inserted in the "receptacle or tub," and the latter supplied with the cleansing compound before or after the insertion of the drum, as may be preferred. The cover is 65 then located over the tub, and motion imparted to the inner drum through the medium of the crank 44, the rotation of the drum causing the garments to be rapidly agitated and turned over and over through 70 the operation of the V-shaped combined deflectors and carriers 47 which thus thoroughly agitate the garments, and cause the liquid to flow through them. As the drum is rotated the hoods 48 passing through the 75 cleansing liquid, elevate the same and cause it to pass through the screen-covered openings and against the deflectors and thereby forcibly thrown against the garments, the plurality of the hoods, openings and deflectors causing a continuous flow of the liquid upon the garments, at the same time the garments are held away from direct contact with the screen covers and the openings, so that the water flows freely through the 80 85 same.

The improved device is simple in construction; efficient in action and thoroughly agitates and "rubs" the garments to cause the disintegration of the dirt and grime.

The improved device may be constructed of any required size or capacity and of any suitable material, but will preferably be of galvanized iron or wood, as before described.

I claim—

1. A drum for washing machines mounted for rotation and having a plurality of elongated openings arranged in circumferentially spaced relation to one another, guideways adjacent to three sides of said openings 100 and foraminous shields independently insertible into said guideways to cover the adjacent openings.

2. A rotatable drum for washing machines including a pair of circular head members, 105 a band connecting the peripheries of the head members and provided with a plurality of openings circumferentially spaced from one another and extending transversely of the band, a removable screen mounted 110 over each of the openings, a cross sectionally V shaped deflector secured on the inner face of the drum adjacent each opening and a hood member for each opening, said hood members extending outwardly at an acute 115 angle with respect to the screen members.

In testimony whereof I affix my signature in presence of two witnesses.

CHARLES O. HOLLIDAY. [L. s.]
